Inventor:

James W. Phelps
Edward Fay Wilson

Atty.

UNITED STATES PATENT OFFICE

JAMES W. PHELPS, OF CHICAGO, ILLINOIS

FLASHING RECEPTACLE

Application filed February 21, 1927, Serial No. 169,906. Renewed July 15, 1929.

My invention relates to improvements in electrical receptacle and has special reference to flashing or electric make and break receptacles.

- 5 This present invention is, in part, a continuation of my co-pending application on electric receptacles, filed May 24, 1924, S. N. 715,556, now Patent No. 1,694,141, issued December 4, 1928.
- 10 The object of my invention is to provide a simple make and break receptacle which shall consist of a minimum number of parts, which shall make use of fasteners for accomplishing more than one function, which shall 55
- 15 be cheap to manufacture and which shall effectively and economically serve its purpose of flashing a lamp.

A particular feature of my invention relates to the securing of the thermo-element 20 and one of the terminals by a single fastening means.

My invention will be more readily understood from the following description taken in conjunction with the accompanying drawing, forming part of this specification and in which:—

Fig. 1, is a vertical, central section of a flashing receptacle on the line 1—1 of Fig. 2, made in accordance with my invention 30 and embodying the invention in one form:

Fig. 2, is a horizontal section taken on the line 2—2 of Fig. 1;

Fig. 3, is a bottom plan view of the receptacle shown in Fig. 1;

Fig. 4, is a fragmental, vertical section on the line 4—4 of Fig. 2;

Fig. 5, is a diagrammatic view, particularly showing the electric circuit;

Fig. 6, is a sectional view similar to Fig. 40 1 taken on the line 6—6 of Fig. 7, and showing a modified form of the invention;

Fig. 7, is a horizontal section on the line 7—7 of Fig. 6; and

Fig. 8 is a fragmentary, vertical section on 45 the line 8—8 of Fig. 7.

In said drawings 1 represents a porcelain receptacle, having a base 2 and an upstanding socket 3. In the socket 3 is a screw-threaded shell terminal 4 of usual form for 50 receiving the common form of screw-

threaded lamp base or other similar connecting device. The base is hollowed out beneath, as shown at 5, for the reception of the thermo-element. As usual the base has perforated securing lugs 6, and between them connection supporting lugs 7 and 8.

The shell terminal 4 has internal flange portions 9 at its lower end for securing the shell in place. I provide a connecting member 10 which is Y-shaped, the arms 11 of which are found to fit within the base of the shell and lie on top of the flanges 9, and the two parts are secured to the base 2 by fasteners 12 which, as shown, are screws extending up through the base and received at 60 their upper ends in screw-threaded openings in the arms 11. The shank or stem 13 of the member 10 extends out through an opening 14 in the shell 4 and a registering opening 15 in the socket 3, and is provided 65 on its outer end, which is positioned above the connection lug 7, with a clamping screw 15' by which one of the circuit wires can be attached to the device. To form the other side of the circuit I provide a central 70 screw 16 which extends down into the hollow base and is held in place by a nut 17 on its lower end.

I arrange a thermo-element 18 in the hollow base, in the form shown consisting of 80 a bi-metal strip 19 wound with a coil 20 through which the current flows to the central contact 16. The inner end of the strip 19 is clamped in place beneath a washer 21 held in place by the nut 17. One end of the 85 heating coil can be clamped to the strip 19 by the nut 17 or it could obviously be soldered thereto.

Upon the connection lug 8 I secure a connection plate 22 by a screw 23 which extends 90 up through a hole provided in the base and engages in a screw-threaded hole provided in the plate at one end. At the opposite end of the plate I provide a binding screw 24, the point of which extends down into a 95 pocket 25 in the base 2, and thus in cooperation with the screw 23 holds the plate 22 in place. At the center of the plate 22 there is provided a vertically adjustable screw 26 mounted on the plate 22 and which extends 100

down into the base for contact with the free end of the thermo strip 19. By adjusting the screw 26 up or down the timing of the flashes can be changed. The circuit is completed by binding the free end 27 of the thermo coil beneath the connection plate 22 by the screw 23. For the purpose of causing the one fastener 16 for the thermo-element to hold it accurately in position, I provide shoulders 28 on the base.

The current enters the device through the binding screw 24 and passes through the plate 22 and coil 20 to center contact 16 and out through the socket and binding screw 15 15'. This heats the coil 20 and causes the bi-metallic plate to close against the adjustable screw 26, thus opening a free course for the current through the strip 19 to light the lamp in the socket. This shunts the current 20 from the coil permitting it to cool and open the main circuit at the contact between the strip 19 and adjusting screw 26, thus cutting off the current from the lamp until the circuit is again closed at this point.

25 In the form of device shown in Figs. 6 to 8 inclusive the arrangement is practically the same as that already described, except that the thermo-element 18, in this instance, is arranged above the base instead of as in 30 the form described. The inner end of the thermo-element in this form is held beneath the top 29 of the center contact 30 which is shown as a hollow rivet which extends down through a central opening in base 2 and has its end turned or bent over in a sunken opening 31 in the bottom of the base.

Instead of the flat connection plate 22 I 40 provide a U-shaped bridge plate 32, having bent out ends to form feet 33 and 34. The binding screw 24 is arranged in the foot 33 and a fastener 35, in this instance, a hollow rivet secures the bridge plate 33 to the base by the foot 34. As before, one end 27 of thermo-coil 20 is clamped under the foot 34. 45 The adjusting screw 26 is mounted in the bent up part of the bridge plate 32 and above the free end of the thermo-strip. To assist in retaining the adjusting screw 26 in its adjusted position I provide a friction plate 36 bent to conform with one end of the bridge plate. One end of this friction plate is clamped tight by the fastener 35, and the other end 37 is formed to press up under the head of the adjustable screw.

55 In the center of the socket I provide a low post 38 upon the top of which the inner end of the thermo-strip is held by the center contact, and to retain the strip from swinging sideways out of its desired position I 60 provide the top of the post with projections 38 between which the thermo-strip is received.

The flow of current through the modified form of device is the same as that already 65 described.

As many modifications of my invention will readily suggest themselves to one skilled in the art, I do not limit or confine my invention to the specific details of construction herein shown and described.

70

I claim:

1. In a receptacle of the kind described, a socket portion upstanding from a base, a shell terminal within the socket, means extending down into the base for securing the shell terminal, a central terminal in the socket, means extending through into the base for securing this terminal in position, a connecting plate extending over the base and into the socket for connection to one of the terminals thereof, a bi-metallic thermo-element within the base secured at one end by the securing means of the central terminal, a second connection plate on the base, an adjustable contact screw carried by said second plate and extending down into the base for contact with the thermo-element, a coil on said element connected at one end to said second connection plate and at the other end to said central terminal, whereby said coil is in circuit when the circuit is open between the adjustable screw and the thermo-element, as and for the purpose specified.

2. In a device of the kind described, a body of insulation material having a hollow base, a shell terminal and a central terminal secured upon the body, a thermo-electric make and break bar arranged in the hollow base extending transversely thereof and secured at one end only by the fastening means of the central terminal.

3. In a wall socket, a body of insulation material having a hollow base, a shell terminal and a central terminal secured on the body, a thermo-electric make and break bar arranged in the hollow base and rigidly mounted at one end by the central terminal fastening means.

4. In a device of the kind described, a body of insulation material having a hollow base, a central terminal and a shell terminal secured to the body by fasteners extending into the base, and a thermo-electric make and break bar arranged in and extending transversely of the base and rigidly held at one end only by the central terminal fastener.

5. In a wall socket, a body of insulation material having a hollow base, a shell terminal and a central terminal, means securing said terminals upon said body, a thermo-electric make and break bar in the hollow base and electrically connected at one end to the central terminal by the securing means thereof.

6. In a wall socket, a body of insulation material, a central terminal and a shell terminal secured to the body, and an electric thermo-element secured on the body by the means securing the central terminal thereon.

125

130

7. In a device of the kind described, a body of insulation material, having a base, a socket thereon, a shell terminal and a central terminal within the socket, means securing said terminals in place, a thermo-electric make and break element on the base and secured by the means securing the central terminal in position.

8. In a wall socket, a body insulation material having a recess, a central and a shell terminal secured to said body, a thermo-electric make and break bar arranged in said recess and secured at one end only by the fastening means of the central terminal.

15 In testimony whereof, I have hereunto set my hand, this 9th day of December, 1926.

JAMES W. PHELPS.
